CUTTER GRINDER

Oscar M. Braaten, Rock Island, Ill., assignor to
 The Cincinnati Milling Machine Co., Cincinnati,
 Ohio, a corporation of Ohio

Application June 10, 1944, Serial No. 539,741

14 Claims. (Cl. 51—50)

1
 This invention relates to grinding machines and more particularly to improvements in cutter grinders.

One of the objects of this invention is to provide an improved and efficient cutter grinder.

Another object of this invention is to provide an improved cutter grinder for sharpening contour helical cutters.

Another object of this invention is to provide an improved cutter grinder for sharpening contour helical cutters which may be set up to cause a grinding wheel to automatically follow the cutting edge of a contoured helical tooth and grinding a substantially constant clearance angle at said edge regardless of the angle of the tooth or the variations in the contour of the cutter.

A further object of this invention is to provide an improved cutter grinder for sharpening contour helical cutters in which each tooth may be accurately ground with a substantially constant clearance angle throughout its length and in a single continuous pass between the grinding wheel and the tooth.

An additional object of this invention is to provide an improved machine for grinding contour helical cutters which has separate adjustable or change devices for generating selective helices, for controlling the contour of the helix by varying the radius thereof, for determining the clearance angle for shifting the phase of the helix whenever compensations for the rake angle of the tooth become necessary.

Other objects and advantages of the present invention should be readily apparent by reference to the following specification, considered in conjunction with the accompanying drawings forming a part thereof and it is to be understood that any modifications may be made in the exact structural details there shown and described, within the scope of the appended claims, without departing from or exceeding the spirit of the invention.

Referring to the drawings in which like reference numerals indicate like or similar parts:

Figure 1 is an elevational view of a mechanism embodying the principles of this invention.

Figure 2 is a section on line 2—2 of Figure 1.

Figure 3 is a plan view of the mechanism shown in Figure 2.

Figure 4 is a detail section on the line 4—4 of Figure 1.

Figure 5 is an end elevation as viewed on the line 5—5 of Figure 1.

Figure 6 is a diagrammatic view of a cutter tooth showing the relationship of the various angles.

2

Figure 7 is a diagram illustrating phase shifting of a generated helix.

This invention relates to improvements in a cutter grinder of the type disclosed in my co-pending application, Serial No. 449,311, which was filed July 1, 1942, and which issued as Patent No. 2,419,529, April 29, 1947.

In the machine shown in said co-pending application it is necessary to use a duplicate cutter of the type to be ground, or a control cam having a tooth formed thereon similar to the tooth of the cutter to be ground as a model to control relative rotative movement between cutter and grinding wheel, which means that in the case of spiral toothed cutters the model must have the same spiral and the same tooth rake angle as the cutter to be sharpened. Due to the large number of possible spirals and the larger number of possible rake angles, the resulting number of different combinations of these two becomes so large as to make it impractical to stock a set of change cams for the machine if the full usefulness of the machine is to be obtained.

By means of this invention separate devices are provided for determining the helix to be generated and the rake angle to be compensated for so that a greater number of combinations can be obtained with less mechanism. Thus the machine of this invention may be preset for grinding a contour helical cutter by the use of a first selective means for determining the clearance angle to be ground at the cutting edge of the cutter, a second selective means for determining the lead angle of the helix to be generated, a third selective means for determining and controlling the radius of the generated helix during its generation and thereby make the generated helix conform to the shape or contour of the cutter to be sharpened, and a fourth selective means which may be preset in accordance with the rake angle of the cutter tooth which is effective during in or out movement of the grinding wheel to effect a phase shift of the generated helix to correct or compensate for errors which might otherwise be introduced to vary the clearance angle whereby a cutter tooth may be ground in a single continuous pass of the grinding wheel relative to the tooth.

The basic structural features of the machine shown herein conform in general to the machine shown in the aforesaid co-pending application and comprise a bed or frame 10 having guideways 11 as shown in Figure 3 for slidably supporting a traversable slide 12 upon which is superimposed a cross slide 13 which, in turn, supports a turn-table 14 that carries a grinding wheel 15 rotat-

ably mounted thereon. The central plane of rotation 15' of the grinding wheel passes through the axis 16' of the turntable whereby the plane of rotation of the grinding wheel may be swiveled about the axis of the turntable.

A headstock 16 is mounted upon the bed or support 13 for supporting a rotatable spindle 17 to one end of which is attached an arbor 18 for supporting a work piece which is a cutter, such as 19, the teeth of which are to be ground or sharpened by the grinding wheel 15. The cutter is frictionally secured and clamped to the arbor by means of locking nut 20 which is threaded on the end of the arbor. This makes it possible to use various sizes of arbors depending upon the size of the bore of the cutter.

The parts are set up for a grinding or sharpening operation by rotatably positioning the cutter 19 on the arbor 18 until a cutting edge such as 23 is positioned in a horizontal plane 21 passing through the axis of the cutter. This positioning of the cutting edge is facilitated by a gage member 24 which is mounted on the side of the headstock as shown in Figure 1 for longitudinal sliding movement on a supporting bracket 25. The gage may be clamped by a clamp screw 26, it being understood that the gage has a longitudinally extending slot formed therein whereby the gage may be moved into or out of engagement with the cutter. After these adjustments have been made the cutter is secured to the arbor by lock nut 20. The grinding wheel is then raised or lowered by adjusting screw 28' with respect to the plane 21 a predetermined amount, as for instance by the amount indicated by the reference numeral 27 in Figure 2 to grind the necessary clearance angle on the margin of the cutter tooth adjacent to the cutting edge. This adjustment is in accordance with standardized practice and the further off center the greater the clearance angle will be.

For a better understanding of this invention and the problems involved, reference may now be had to Figure 6 which shows a conventional cutter tooth, the tooth itself being indicated generally by the reference numeral 28. These teeth are formed by cutting longitudinally extending slots or gullets 29 in the periphery of the cutter body and the shape of this gullet is such as to form the cutter face 30. The tooth also has a cutting edge 23, a margin 31 and a secondary clearance or relief 32 on the back of the tooth. The gullet may be cut in such a manner that the tooth face 30 lies in the radial plane 33, in which case the face is said to be radial, or it may be at an angle to this plane in which case it has a positive or a negative rake angle. The face 30, for instance, is shown as having a positive rake angle, the value of which is indicated at 30a but if the tooth face fell on the line, identified by the reference numeral 34, it would have a negative rake angle, the value of which is indicated at 34a. The margin is the surface to be ground in order to sharpen the cutter and to give it clearance at the same time. The angle which this margin makes with a tangent 35 to the cutter constitutes the clearance angle which is identified by the reference numeral 29.

In a cutter having a helical cutting edge, the helix of this edge may be generated mathematically by revolving a straight radial line about the axis of a cutter in screw-like fashion so that as it revolves it also moves axially. This means that each radial element of the surface produced is a straight line. Thus a control cam may be

generated in the same manner and since each element of the generated surface is a straight line a cam follower utilized therewith may move radially in or out with respect to the cam axis 6 without causing rotation of the cam, but movement of the follower parallel to the cam axis regardless of its radial distance therefrom will cause rotation of the cam and will produce the same angular rotation regardless of its radial distance from the cam axis. The distance that the line moves along the axis of the cam during one rotation about the cam axis may be designated as the lead and corresponds to the lead of the helix.

15 In view of this latter fact, it is not necessary to make the control cam the same diameter as the cutter with the result that the diameter of the cams may be standardized but still each cam will cover all diameters of cutters having the same helix. The radius of the cam, however, should be made great enough to take care of the maximum depth of gullet which would represent the maximum movement of the grinding wheel in moving from the periphery of the cutter to the bottom of the gullet.

20 25 The change helix cams, such as the one indicated by the reference numeral 37 in Fig. 1, are generated in this manner and this method results in a saving in the number of cams and 30 also a saving in the expensive material of which the cams are made.

35 As shown in Figure 1, the cams are mounted on an arbor 38 which projects from the opposite end of the headstock from the cutter arbor and is secured to the spindle 17 for controlling rotation 40 of the cutter, or in other words, generation of a helical grinding path corresponding to the helix of the cutting edge being ground. The cam is frictionally secured to the arbor by a lock nut 38 threaded on the end of the arbor in a similar manner utilized for clamping the cutter. In order to control rotation of the cam in accordance with longitudinal movement of the grinding wheel and in timed relation therewith so that 45 the cutting edge is always in proper position with respect to the grinding wheel, a follower 43 is provided for engagement with the generated or control surface of the cam and since it is necessary that this follower partake of both directions 50 of movement of the grinding wheel it is carried by a bracket 41, Figure 1, which is attached to the cross slide 13. Thus, the bracket moves in and out with the cross slide 13 and longitudinally with the traversing slide 12.

55 60 65 The grinding wheel is caused to follow the contour of the cutter by means of a contour controlling cam 42 which has the same contour as the cutter to be sharpened and which is removable and interchangeable with other cams and is attached to a cross adjustable slide 43 by means of clamping screw and nut 44. The slide 43 is adjustable on the main frame 10 to take care of variations in the diameter of cutters being ground, it being necessary that the edge of the cam 42 be in vertical alignment with the cutting edge of the cutter as shown in Figure 2. The turn table 14 carries a follower pin 45 for the cam 42 which is also interchangeable and which is of a radius equal to the smallest radius in the contoured outline of the cutter. The grinding wheel 15 is also chosen of such width that the periphery thereof may be trued to a radius equal to the radius of the pin 45. The grinding wheel 70 75 is positioned so that the center of its semi-circ-

cular face is in vertical alignment with the center of the pin 45 and thus over the center of the turntable. The contour cam 42 coacting with the follower pin 45 thus constitutes means for determining and controlling the radius of the helix generated by the cam 37.

Attention is invited to the fact that if a spiral contoured cutter tooth has a radial face, i. e., zero rake angle, as explained in connection with Figure 6 that any in or out movement of the grinding wheel will not effect the size of the clearance angle, and in addition, it will be noted that if the follower 49 were rigidly attached to the slide 13 that this in or out movement will not cause rotation of the cam 37 due to each element of the cam surface being a radial straight line, but it will also be noticed that traversing movement of the slide 12 will cause rotation of the cam and thereby of the cutter in accordance with the helix of the cutting edge.

On the other hand, if the cutter tooth face has a positive or negative rake angle another problem is introduced for which correction must be made. Referring again to Figure 6 and considering the cutter face 30 it will be seen that as the grinding wheel moves radially inward toward the axis 22 that the cutting edge would progressively drop below the radial plane 33 since the cutting edge must always lie in the face of the tooth. This would cause a decrease in the clearance angle. In other words, suppose that the grinding wheel 15 moves from the large diametric portion 46 of the cutter shown in Figure 1 to the smaller diametric portion 47, corresponding to distance 47' for instance in Figure 6, the cutting edge would recede to the point 48. The cutting edge would then be below the plane 33 and by reference to Figure 2 would be ground by a peripheral portion of the wheel which is nearer the center of the wheel, and thus more vertical which automatically reduces the clearance angle.

By means of this invention a correction is effected by providing means for imparting a corrective rotative movement to the cutter as the grinding wheel moves toward or from the cutter axis, thus maintaining the cutting edge at all times on or in the radial plane 33 whereby the same angular relation is maintained between the marginal surface 31 and the portion of the grinding wheel in contact therewith regardless of 50 radial movement of the wheel. This means comprises a rake angle compensating mechanism.

Referring to Figure 5, this mechanism includes a pivoted lever 49 which has the follower 40 attached to one end thereof and a second follower 55 attached to the other end. The lever arms of the two followers are equal and the lever is pivotally supported in the middle on a pin 51 carried by a bracket 52. It will be noted that the center of the pin lies in a plane which is tangent to the 60 tips of the followers. The follower 50 is adapted to contact an angularly adjustable template 53 which is in the form of a flat plate and this plate constitutes the means that is set in accordance with the rake angle to impart the necessary compensating rotation to the control cam. The bracket 5 is dovetail guided at 54 in a slidable support 55.

It will be noted from this that the bracket 52 may be adjusted transversely to the direction of 70 adjustment of the support 55. The support 55 is mounted in a T-slot guideway 56 of a bracket 57 which is part of the previously mentioned bracket 41 secured to the grinding wheel cross slide 13. Thus, the two followers 40 and 50 par-

take of the in and out and transverse movements of the grinding wheel.

The plane 51a which contains the center of the pin 51 and is tangent to the ends of the followers, also passes through the center 59 about which the template 53 is angularly adjusted and this plane is co-incident with the radial plane 33 of Figure 6 or the radial plane 21 of Figure 2 in which the cutting edge of the cutter lies. As shown in Figure 1 the template 53 has an enlarged head 60 from which projects an integral round stud 61. This stud passes through a bore 62 in an adjustable cross slide 63 and also an elongated slot 64 formed in an upstanding bracket 65 as shown in Figure 4. This bracket is attached by bolts 66, Figure 5, to the base of the headstock 16. The cross slide 63 may be longitudinally adjusted and secured in position by a clamping screw 67. The template 53 may be angularly adjusted by loosening the lock nut 68 which is threaded on the end of the stud 61 and this rotational adjustment is independent of the cross slide 63. The angle of adjustment may be determined by graduations 69 formed on the head 60 in conjunction with a zero mark 70 carried by the cross slide. It can be mathematically determined what the angle of adjustment of the template should be for each different rake angle, but in practice a simpler method is used. The operator when setting up the machine moves the grinding wheel which is stopped at this time into engagement with a tooth on the smallest diameter of the cutter with the point of contact lying in a plane connecting the centers of the wheel and cutter.

The follower 40, being integrally connected with the grinding wheel, would partake of this movement and thus be moved into engagement with a small diameter of the control cam. The template 53 is then adjusted by means of its various supports so that the center 59 engages the follower 50. The grinding wheel is then moved out and into engagement with the largest diameter of the cutter and with the same tooth. 45 Due to the helix of the tooth and the rake angle of the tooth face, the cutter must be rotated to bring the cutting edge into contact with the same contact portion of the wheel as for the first positioning. Corresponding rotation of the control cam will occur.

It should be noted that the total resultant rotation of the cam which is produced at this time is the resultant of two independent actions or in other words is composed of two independent components. The first component is the rotation due solely to the helix, and the second, rotation due to the rake angle. Since the lead of the helix of the cam is the same as the helix of the cutting edge, the rotational component due to the helix will not cause any displacement up or down of the follower 40. The second rotational component, however, will cause displacement of the follower 40 and thus of follower 50. The template 53 is then angularly adjusted into contact with follower 50 and clamped.

It will now be evident from Figure 5 that movement of the followers 40 and 50 to the right or left which would correspond to in or out movement of the grinding wheel with respect to the cutter will cause rotation of the cam 37 either clockwise or counterclockwise as the case may be and thereby impart a deviation or shift of the helical grinding path being generated between the cutter and grinding wheel. This deviation corresponds to a phase shift of the helix. This is

best represented by a diagram such as shown in Figure 7 in which axial movement of the generatrix is plotted against rotation. Uniform movement in both directions produces the straight line 71 which represents the helix. A direct in or out movement of the grinding wheel unaccompanied by any traversing movement will cause a rotation only which is represented by the line 72. If the grinding wheel then traverses on a constant diameter of the cutter the helix picks up again and is represented by the line 73. The helix has, therefore, experienced a phase shift to the left by the amount indicated at 74. Thus, in or out movement of the grinding wheel effects a phase shift of the initial helix.

Attention is invited to the fact that the frictional urge imparted by the grinding wheel on the cutter during grinding is such as to produce a clockwise urge on the cutter and thereby on the cam 37 as shown in Figure 5 which reacts through the followers and the lever 49 to maintain the follower 50 in contact with the template 53. Thus, by rotating the grinding wheel 15 in a counterclockwise direction all lost motion is taken up in the various connections.

After one tooth of the cutter has been ground the locking nut 20 is loosened, the cutter rotated one tooth which is brought into alignment with gage 24, and the cutter secured again to its arbor by the lock nut 20. By this means the cutter may be indexed relative to its control cam and thus the one control surface on the cam will suffice for all teeth of the cutter. It will be noted that after the template 53 has been adjusted to the proper angle to compensate for the rake angle of the tooth that in and out movement of the grinding wheel will cause movement of the follower 50 relative to the plate 53 and thereby rotation of the lever arm 49 and follower 40 imparting rotation to the cam 37, to compensate for the rake angle of the cutter and maintain the cutting edge thereof always in the plane 33 and thus the proper clearance angle on the margin 31.

There has thus been provided an improved cutter grinder which is especially adapted for grinding helical contour cutters and which by use of very simplified means is adapted to accurately maintain the proper angular relationship between the cutting edge of the cutter and the grinding wheel and thus the proper clearance angle during transverse or crosswise movements of the grinding wheel and regardless of the helical lead, the diameter of the cutter, or the shape of the contour.

What is claimed is:

1. In a cutter grinder having a rotatable work support and a grinding wheel support mounted for two-directional relative bodily movement in a plane parallel to the axis of the work support, a plane parallel to the axis of the work support, co-acting means between the supports for imparting rotation to the work support during relative bodily movement between the supports in a path parallel to the axis of the work support and other co-acting means effective upon departure from said parallel path to impart an additional component of rotative movement to the work support.

2. In a cutter grinder, a work support, a grinding wheel support mounted for two-directional movement relative to the work support, co-acting means responsive to movement in one direction for causing rotation of the work support and other co-acting means responsive to movement transversely of the first-named movement for imparting an additional component of rota-

tion to the work support either in the same or opposite direction to the first-named rotation.

3. In a cutter grinder for sharpening helical contour cutter teeth formed with a rake angle and having a cutter support, a grinding wheel support and a rotatable grinding wheel mounted thereon, the combination of coacting means for maintaining the cutting edge of the cutter teeth in predetermined relation with the periphery of the grinding wheel during relative bodily movement of the wheel including a first cam means between the supports for determining the contour of the cutter, a second cam means for controlling rotation of the cutter and thereby the lead of the helix and a third cam means coacting with the second cam means for imparting a corrective movement to the second cam means in accordance with the rake angle.

4. In a cutter grinder having a main support, 20 a work supporting spindle journaled in the main support, a grinding wheel support having a grinding wheel mounted thereon, said grinding wheel support being guided for two-directional movement relative to the work supporting spindle, the combination of means to secure a spiral cutter to said spindle, a cam operatively connected to said spindle, a follower carried by the grinding wheel support for engagement with said cam for controlling rotary movement of said spindle during traversing of the grinding wheel support, and additional means carried by the main support and coacting with said follower for imparting corrective movements to the first-named cam during traversing of the grinding wheel.

5. In a cutter grinder having a rotatable work supporting spindle, a grinding wheel, a support for said grinding wheel movable in two directions relative to said spindle, the combination of a profile cam mounted on the main support and coacting with the grinding wheel support for causing the grinding wheel to follow the contour of a cutter being ground, a helical cam having a straight line radial element, a follower therefor carried by the grinding wheel support for imparting rotary movement to the work spindle during traversing of the cutter, additional cam means carried by the main support and operatively connected to the follower for phase shifting the helical movement in accordance with the rake angle 50 of the grinding wheel during radial movement thereof with respect to the work spindle.

6. In a cutter grinder for sharpening helical contour cutters, the combination with a cutter support and a grinding wheel support relatively movable in two directions, a contour cam carried by one of said supports, a follower carried by the other support coacting with the profile cam, a helix determining cam operatively connected for rotation of the cutter, a follower for 60 said cam and operatively connected with the grinding wheel support, and additional cam means carried by the main support and coacting with said follower for imparting rake angle compensation to the helical cam during relative radial movement between said supports caused by the contour cam.

7. In a cutter grinder having a rotatable spindle for supporting a cutter to be sharpened, a grinding wheel, means to support said grinding wheel 70 for two-directional movement relative to said spindle, a helical control cam attached to said spindle, each element of said cam being a straight radial line perpendicular to the axis thereof, a follower for said cam operatively connected to the grinding wheel support whereby radial move-

ment of the grinding wheel with respect to the cutter will not effect rotation of the cam but traversing movement will effect rotation of the cam, and means to effect a corrective positioning of the follower during radial movement of the grinding wheel.

8. In a cutter grinder having a work supporting spindle and a grinding wheel supported for two-directional movement relative to the spindle, the combination of cam means carried by the spindle and a follower carried by the grinding wheel support for causing rotation of the spindle in timed relation to the longitudinal movement of the grinding wheel support, means to pivotally support the follower on the grinding wheel support, and a relatively fixed sine bar coacting with the pivoted follower for imparting compensatory movements thereto in accordance with the rake angle of the cutter being sharpened during radial movement of the grinding wheel relative to said spindle.

9. In a cutter grinder having a work supporting spindle, means for attaching helical contour cutters to said spindle, a grinding wheel supported for two-directional movement relative to said spindle, cam means attached to said spindle for imparting rotary movement to the cutter during longitudinal movement of the grinding wheel, a pivoted lever carried by the grinding wheel support, followers attached to opposite ends of the lever, one of which coacts with said cam, additional cam means coacting with the other follower for imparting movement to the cam during radial movement of the grinding wheel with respect to the spindle.

10. In a cutter grinder having a work supporting spindle, means for attaching helical contour cutters to said spindle, a grinding wheel supported for two-directional movement relative to said spindle, cam means attached to said spindle for imparting rotary movement to the cutter during longitudinal movement of the grinding wheel, a pivoted lever carried by the grinding wheel support, followers attached to opposite ends of the lever, one of which coacts with said cam, additional cam means coacting with the other follower for imparting movement to the cam during radial movement of the grinding wheel with respect to the spindle, the arms of said lever being 50 of equal length and said pivot being mounted parallel to the axis of the spindle.

11. In a cutter grinder having a main support, a work supporting spindle journaled therein, a grinding wheel and means for supporting the 55 grinding wheel for two-directional movement relative to said spindle, the combination with means for attaching a helical contour cutter to said spindle having a helical cutting edge, and means attached to said spindle and coacting with 60 said grinding wheel support for maintaining that portion of the cutting edge being ground in a predetermined radial plane during radial or traversing movements of the grinding wheel to insure the formation of a constant clearance angle at 65

the cutting edge regardless of changes in the contour of the cutter or the spiral angle of the cutting edge.

12. In a cutter grinder having a work supporting spindle, a grinding wheel and means for supporting the grinding wheel for two-directional relative movement with respect to said spindle, the combination with a cam on said spindle and a follower carried by the grinding wheel support 10 for causing rotary movement of the spindle during traversing of the grinding wheel, a relatively fixed sine bar, means to adjust the angular relation thereof with respect to a radius of said cam, a follower for said sine bar and operatively connected to the first-named follower for varying the position of the latter during radial movement of the grinding wheel with respect to the work supporting spindle.

13. In a cutter grinder having a work supporting spindle and a grinding wheel supported for two directional movement relative to said spindle for sharpening the cutting edge of a helical contour cutter attached to said spindle, the combination of a first means to cause rotation of the 20 spindle and cutter in timed relation with traversing movement of the grinding wheel, and other means for imparting an additional rotation to the spindle in the same or opposite direction during uniform movement of the grinding wheel 25 toward or from the axis of the cutter.

14. In a machine for grinding the clearance angle at the cutting edge of a spiral contour cutter, the combination of a grinding wheel having an arcuate grinding face, means to relatively 30 adjust the center of the grinding wheel normal to a radial plane of the cutter which passes through the cutting edge to establish a prescribed clearance angle at said edge, separate supporting means for the grinding wheel and cutter guided for relative traverse and lateral movements, means 35 interconnecting said supporting means for imparting rotation to the cutter in response to either direction of movement, means for controlling the extent of said lateral movement and thereby the 40 contour of said cutter, and means for supporting the grinding wheel for oscillation about an axis perpendicular to said radial plane and passing through the center of curvature of the periphery of the grinding wheel.
